UNITED STATES PATENT OFFICE.

JOHANN HEINRICH HERMANN VOSS, OF WHITE PLAINS, NEW YORK, ASSIGNOR TO WORTHINGTON PUMP AND MACHINERY CORPORATION, OF NEW YORK, N. Y., A CORPORATION OF VIRGINIA.

AUTOMATIC PLATE VALVE.

Application filed December 31, 1921. Serial No. 526,158.

To all whom it may concern:

Be it known that I, JOHANN HEINRICH HERMANN Voss, a citizen of the German Republic, residing at White Plains, county 5 of Westchester, and State of New York, have invented certain new and useful Improvements in Automatic Plate Valves, fully described and represented in the following specification and the accompanying drawings, forming a part of the same.

This invention relates to automatic plate valves adapted for use in high speed gas and air compressors and the like, and especially to automatic plate valves of the class that 15 function by bending and are free from localized bending with its resulting crystallization of the metal and early fracture, the especial object of the invention being to provide an improved valve of this class, in 20 which the valve shall be properly held in position and guided in its opening and closing movements with the minimum of friction and wear on the valve seat and valve.

For a full understanding of the invention a detailed description of a construction embodying the invention in preferred forms 25 will now be given in connection with the accompanying drawings forming a part of this specification, and the features forming the 30 invention then be specifically pointed out in the claims.

In the drawings:

Fig. 1 is a cross section of a complete valve structure, transverse to the ports and 35 valve plates;

Fig. 2 is a section on the line 2—2 of Fig. 1;

Fig. 3 is a sectional plan of Fig. 1 approximately on the line 3—3, with the valve 40 seat partly broken away to show the construction, and

Figs. 4, 5, 6 and 7 are detail sections similar to Fig. 2 showing modifications.

Referring now to the drawings and especially to Figs. 1 to 3, A is the valve seat, shown as of circular form and having the series of straight ports a, each of which is controlled by a plate or strip valve b, which opens against the abutment and holding strip c between the valve seat A and the abutment block C, which abutment C has a series of ports d out of line with the ports a and valves b. The abutment block C preferably has a sleeve extension D, as shown,

which extension encloses the valve seat A 55 and is screw threaded beyond the valve seat to receive the holding block E shown as consisting of a spider having a recess 10 at the hub for receiving the usual holding screw for securing the valve in place. 60

Each of the valves a consists of a thin strip of metal free to bend uniformly so as to avoid localized bending, these valves being substantially the same in construction and function as described and claimed in 65 Meyer Reissue Patent No. 13991, dated October 12, 1915, and Patent No. 1,341,145, dated May 25, 1920, except for the features forming the present invention.

In accordance with the present invention, 70 as illustrated in Figs. 1 to 3, the valves b and the corresponding abutment strips c are formed with bent ends 1, 2 projecting into recesses 3 in the abutment block C, and the valves and abutment strips are spring seated 75 near their ends and preferably at the bends, by coil springs e seated in holding recesses in the abutment block C, so that a yielding abutment is thus formed for the ends of the valves b. The bent ends of the valves b and strips c are curved so as to permit the ends 80 of the valves to roll on the abutment strip ends freely as the valves bend in opening and closing, the radius of curvature at contact preferably being approximately the 85 same, although efficient action may be secured with the radius of curvature of the valve ends being somewhat larger than the radius of curvature of the abutment strips. The abutment strips c preferably are elastic 90 so as to form an elastic abutment for the valves b in their opening movement, but they may be of such thickness or material as to be rigid. With this construction, the sliding motion of the valve ends on the valve 95 seat or abutment in the functioning of the valve is reduced to a minimum, the valve ends rolling on the abutment strip with substantially no dragging and, with the spring-seated abutment strip, providing for a slight 100 lift and rolling movement of the valve ends on the valve seat without substantial dragging or pressure thereon. The wear on the valve and valve seat is thus reduced, and the valve seat kept clean at the valve ends. 105

The construction shown in Fig. 4 is substantially the same as above described, except that the abutment or backing strip c is

omitted and the abutment block C is provided with curved surfaces for co-action with the curved ends of the valves b, the elastic abutment being provided by spring f bearing directly against the valves, these springs being shown as of a different form from those of Figs. 1 to 3 and made from a strip of metal rolled into a spiral.

The construction shown in Fig. 5 is the same as those shown in Figs. 1 to 4, except that the abutment strip is omitted and the valve ends do not roll directly on the abutment or spring, but on bearing blocks g set into recesses in the abutment block C and backed by coil springs 4, these blocks being formed with curves co-acting with the curved ends of the valves b in the same manner as described in connection with the abutment strips of Figs. 1 to 3.

20 The construction shown in Fig. 6 is the same as that shown in Fig. 5, except that the elastic seating of the blocks g is omitted so that there is no elastic seating of the valve ends or lifting of the valves against 25 spring pressure, but the valve ends simply roll on the rigid blocks g and the valve seat.

The construction shown in Fig. 7 is similar to that shown in Figs. 1 to 3, except that the valve b is not curved at the 30 ends, but the valve is straight and these ends parallel with the valve seat. The advantage of the curved end valves of Figs. 1 to 6, therefore, is not obtained, but the 35 elastic seating of the valve ends provides for some lifting movement of the valve, and this, especially with the abutment strip between the springs and valve ends, aids in securing the proper holding and action 40 of the valves. The springs are made so light that localized bending is substantially avoided, the curve on the abutment strip being such as to aid in securing this result.

45 It will be understood that the invention is not limited to the detail construction or arrangement of parts illustrated, but that modifications may be made by those skilled in the art while retaining the invention defined by the claims.

What is claimed is:

1. The combination of a valve seat having one or more ports, one or more thin elastic plates forming valves and free to 55 permit uniform bending and having their ends curved away from the valve seat, and an abutment having resilient surfaces on which said curved ends bear in the opening and closing movements of the valve.

60 2. The combination of a valve seat having one or more ports, one or more thin elastic plates forming valves and free to permit uniform bending and having their ends curved away from the valve seat, an 65 abutment having resilient surfaces on which

said curved ends bear in the opening and closing movements of the valve, said surfaces being curved to co-act with the valve curves in securing an easy movement of the valves in opening and closing without localized bending of the valve ends.

3. The combination of a valve seat having one or more ports, one or more thin elastic plates forming valves and free to 75 permit uniform bending and having their ends curved away from the valve seat, a cap, and separate abutment plates for the valves interposed between the cap and the valves and having surfaces on which said curved ends bear in the opening and closing movements of the valve.

4. The combination of a valve seat having one or more ports, one or more thin elastic plates forming valves and free to 85 permit uniform bending and having their ends curved away from the valve seat, a cap, and separate thin elastic abutment plates for the valves interposed between the cap and the valves and having surfaces on which said curved ends bear in the opening and closing movements of the valve.

5. The combination of a valve seat having one or more ports, one or more thin elastic plates forming valves and free to 95 permit uniform bending and having their ends curved away from the valve seat, separate abutment plates for the valves interposed between the cap and the valves and having surfaces on which said curved 100 ends bear in the opening and closing movements of the valve, and a spring backing for the ends of the abutment plates.

6. The combination of a valve seat having one or more ports, one or more thin elastic plates forming valves and free to 105 permit uniform bending and having their ends curved away from the valve seat, a cap, and separate abutment plates for the valves interposed between the cap and the valves and having surfaces on which said curved ends bear in the opening and closing movements of the valve, said surfaces being curved to co-act with the valve curves in securing an 110 easy movement of the valves in opening and closing without localized bending of the valve ends.

7. The combination of a valve seat having one or more ports, one or more thin elastic plates forming valves and free to 120 permit uniform bending and having their ends curved away from the valve seat, a cap, separate abutment plates for the valves interposed between the cap and the valves and having surfaces on which said curved 125 ends bear in the opening and closing movements of the valves, said surfaces being curved to co-act with the valve curves in securing an easy movement of the valves in opening and closing without localized bend- 130

ing of the valve ends, and a spring backing for the ends of the abutment plates.

8. The combination of a valve seat having one or more ports, one or more thin elastic plates forming valves and free to permit uniform bending, a cap, abutment plates for the valves interposed between the valves and cap, and a spring backing for the ends of the abutment plates forming a resilient

10 backing for the ends of the valves.

9. The combination with the valve seat A and valve b consisting of a thin elastic plate free to permit uniform bending and having bent ends 1 formed by a curve away from the valve seat, of valve cap C having recesses 3 receiving the bent ends of the valve.

10. The combination with the valve seat A and valve b having bent ends 1 formed by a curve away from the valve seat, of valve cap C having recesses 3 receiving the bent ends of the valve, and curved bearing surfaces for the curved portions of the valve ends.

11. The combination with the valve seat A and valve b having bent ends 1 formed by a curve away from the valve seat, of valve cap C having recesses 3 receiving the bent ends of the valve, and spring seated

curved bearing surfaces for the curved portions of the valve ends.

12. The combination with the valve seat A and valve b having bent ends 1 formed by a curve away from the valve seat, of valve cap C having recesses 3 receiving the bent ends of the valve, and an abutment strip having curved bearing surfaces for the curved portions of the valve.

13. The combination with the valve seat A and valve b having bent ends 1 formed by a curve away from the valve seat, of valve cap C having recesses 3 receiving the bent ends of the valve, and an abutment strip having spring seated curved bearing surfaces for the curved portions of the valve.

14. The combination with a valve seat A having straight ports and plate valves controlling said ports, of cap C having a flange enclosing the valve seat with a flange projecting beyond the valve seat and screw threaded on the inside, and a holding member screwed into the flange against the valve seat.

In testimony whereof, I have hereunto set my hand.

JOHANN HEINRICH HERMANN VOSS.
